J. Willard,

Brick Machine,

Patented June 10, 1830.

Julius Willard, of Baltimore, State of Maryland.

Letters Patent.

The schedule referred to in these Letters Patent and making part of the same containing a description in the words of the said Julius Willard, himself of his Improvement in the Brick Press called the "Willard's Bridle Brick Press".

To all to whom these presents shall come,

Be it known that I Julius Willard of ^{the City of} Baltimore, Baltimore County and State of Maryland, have invented a new and useful improvement in the Brick-press called "Willard's Bridle Brick Press," and that the following is a full and exact description of the construction and operation of the said machine as invented by me, to wit.

In the annexed drawing A, B, C, D, is a substantial wooden frame about 4 feet long, 2 ft. 6 inches high, and from one foot to one foot six inches wide, the corner posts may be six inches square and the rails E, F, G, H, about three inches thick, by twelve inches deep, the whole being mortised and strongly pinned together and connected by cross-pins, two semicircles are notched out in the upper edge of the rails G, H, to receive and permit to move freely without touching the cylindrical brass-work rods, (C, C,) of the main lever (L,) which together with the lower use of iron, and cast solid, the arms C, C, projecting over the rails and have square shoulders with two round pinions Z; also along their sides towards the short arm of the lever (L,) is cast a square tongue (T,) (scarcely perceptible in the drawing,) the outer ends rest in the bottom of the groove, faced with iron on the inner surfaces of the rails G, H, (not seen in the drawing,) and serve at one pair of the operation as a fulcrum or resting points for the lever (L,) which will be explained hereafter. L, is the piston stand which is also cast iron having near its base and a square shoulder, in which the extremity of the short arm of the lever (L,) is held on it, the foot descends through a large square mortise (R,) in a wooden cross piece (N,) framed into the rails G, H, and is acted on by five governing screws, in the cross piece N, only one of which is seen in the drawing, for the purpose of levelling the piston or moveable bottom plate of the mould, which is

firmly attached by nuts and screws on its upper ends, (S) is one iron casting of the wrought iron bridle (the other not being seen in this view of the machine) both of which attach by means of circular eyes in their lower ends to the round pinnion (P) of the arms (c, c,) of the main lever (L) and have their upper ends made fast to the bridle head R by two screw nuts, (r, r,) above and below R in such manner that by unscrewing these nuts (r, r,) the top plate T of the mould fastened to the bridle head R by the screws and nuts q, q, may be adjusted so as to fall level on the upper edge of the mould W.W. which is a common bridle plate of wrought iron fitted and firmly fastened by screws or otherwise between the upper rails F, F. - and to make it still more permanent, bracing rods (f) are made to connect the opposite ends of the mould. (T,) is the wrought iron framing lever, but in the manner shown in the drawing and having a square eye, by which it attaches to the square pinnion (P) of the cast iron arm (O) which has its bearing in iron eyes, (d) attached to the post P and is cast solid with an arm (m) the end of which is connected by pins and the bridle or wrought iron straps (b, b,) to the extremity of the long arm, of the main lever (L,) forming a parallel joint - the piston stand (P) is also operated on by a similar attachment on the small wrought iron hand lever (V) which may be called the discharging lever. Now when the framing lever T. is thrown back, in the position shown in the drawing, its weight falling on one side of its attachment (n) by reason of its bent form, causes the long arm of the main lever L to rise and the bearing or fulcrum being on the tongue t in the bottom of the groove above mentioned, a correspondent rise takes place in the cylindrical arms c, c, and also in the bridle head R and its attached top plate T; the bridle being thus relieved, whilst the main lever continues to rest on the tongue t it is thrown back till its straps S are checked by the ends of the small wooden springs g, fastened on the outside of the rails F, F, for that purpose. The clay (tempered in the usual way) is then introduced into the mould W.W. after which the bridle is replaced by moving it in a contrary direction till the straps strike the ends of the wooden strips or checks K, (adjusted so as to stop the plate T, precisely over the mould) the framing lever T is then brought down so as to press the long arm of the main lever L, so the post part of the main lever to close the top plate T on the upper edges of the mould W.W. and the moment this takes place, the arms c, c, may be released, the bearing on the

bracket, is actuated and the whole drops upon the circular top $\frac{1}{2}$ of the
bridle S of the bridge, and whilst it serves as a support for the lever I, by the
end arm of which the piston head P is forced up and compresses the brick, also
serves to press down the top plate T under the bridge head R. After the pressure is
finished, the lever I, is thrown back, the bridge head is taken off as before and on
bearing down the lever V, the piston head P is forced up and the brick dislo-
-ys from the mould.

Now what I claim as new and as my own
invention, is the application of the bridge S.R.S. and the peculiar form and applica-
tion of the main lever (I.) and its connexion with the bridge S.R.S by which
the upward and downward pressures, i.e. the downward pressure on the piston
P or the top plate T, and the upward pressure on the piston head P or its plate,
are made to react on each other, also the application and arrangement of the
parallel joint, other levers and governing screws to aid for this special pur-
pose. Given under my hand this 27th day of April 1830.
